UNITED STATES PATENT OFFICE.

FRANCOIS DUFRESNE, OF ST. LAURENT, QUEBEC, CANADA.

SASH-BALANCE.

1,223,861.

Specification of Letters Patent. Patented Apr. 24, 1917.

Application filed June 11, 1915, Serial No. 33,613. Renewed March 21, 1917. Serial No. 156,299.

To all whom it may concern:

Be it known that I, FRANCOIS DUFRESNE, a subject of the King of Great Britain, and residing at St. Laurent, in the Province of 5 Quebec, Canada, have invented certain new and useful Improvements in Sash-Balances; and I do hereby declare that the following is a full, clear, and exact description of the same.

10 The invention relates to that type of sash balance in which the sashes are arranged to slide up and down and to be swung inwardly in a horizontal plane for cleaning purposes.

15 The object of the present invention is to improve the sash cord running devices in order to facilitate renewing or repairing of the sash cords.

It has been proved in practice that the 20 best method of securing easy running of the sashes is to support each sash from balance weights on both sides of the sash, but a great difficulty has been here encountered in view of the fact that when the sash is 25 swung on its hinges, the sash cord attached to the free end of the sash must be either attached or manipulated in some other way in order to permit the sash to be so opened. This invention, therefore, includes means 30 to facilitate the operation of opening the sash.

The invention will now be described in connection with the accompanying drawings, in which the figure shows an inside 35 view of the window with the innermost sash swung inwardly and with part of the window casing in section.

Referring to the drawings, 1 and 2 designate respectively the vertical sides of the 40 window casing which diverge from the outside in order that the light entering the window will be spread over a large area.

The side 1, preferably in one piece is provided with vertical slide grooves extending 45 from top to bottom thereof. Each of the slide grooves is separated from its neighbor by the usual parting strips and have removable outer end strips 14 and 15 extending from top to bottom of the slide 50 grooves.

Each slide groove contains a sash separating strip 19 of sufficient width to extend partly outside the groove. Thus each separating strip is well guided in its vertical slide movement not only by the slide groove

and parting strip, but by the outer end strip also.

24 and 25 are the sliding sashes secured respectively to the supporting strips 19 by the hinges 26.

In order that the window may have a well balanced appearance from the inside, that is to say, in order that the window frame may be centrally positioned within the opening of the wall, it has been found 65 very convenient to arrange for all of the weights to move up and down at one side only of the window; this being the side 2 or in other words, that side opposite the supporting strips. The sash compartment is 70 indicated to the outside of the side 1 by the numeral 32.

Attention is now called to the drawings, which clearly show the counterbalancing arrangement for the sash 25 and it will be 75 noticed that there are a pair of sash cords 34 and 35 for each sash and also a pair of counterbalance weights 36 and 37 attached to the outer ends of these cords respectively. The cord 34 is connected to the supporting 83 strip 19 of the sash 25 and extends over a pulley 38, suitably supported, across to a pulley 39 and thence down the innermost compartment 32 where it is attached to the weight 36.

The pulley 39 is a double one, that is to say, two pulleys are arranged on the same spindle side by side and the cord 35 runs over the other one of these pulleys and down the innermost compartment 32 where it is 90 attached to the weight 37. Particular attention is drawn to the fact that the weight 37 is disposed above the weight 36 in the same compartment and loosely encircles the cord 34, thus permitting it to slide up and down 95 on said cord. The inner end of the cord 35 is connected to the free edge of the sash 25 in any suitable readily detachable manner, and as here shown, a recess 40 is cut in the said free edge of the sash and a groove 41 100 runs therefrom to the top of the sash while the end of the cord 35 is provided with an ordinary sash cord hook 42, engaging the recess 40 while the cord extends upwardly within the groove 41.

In order to swing the sash 25 inwardly, on its hinges, the hinged strip 28 is first thrown back as indicated in the figure in order to open up the groove. The sash 25 is then slid up until it is level with the strip 110

28 and its free edge is then pulled inwardly a short distance which, as will readily be seen, has the effect of pulling on the cord 35 without affecting the cord 34. During 5 this pull on the cord 35, the weight 37 slides on the cord 34 independent of the weight 36. The inner end of the cord 35 is now detached from the free edge of the sash 25 and the latter can be fully opened.

10 It is important to notice that when the cord 35 is released from the sash 25, the weight 37 does not fall to the bottom of its compartment, but remains resting on the weight 36, therefore when reclosing the sash, 15 it is not necessary to have to climb to the top of the window in order to grasp the end of the cord again. Furthermore, when the cord 35 is detached from the sash, the latter remains counterbalanced by exactly the same 20 weight as in the closed position. Of course, it is possible to provide a single weight in place of the two weights 36 and 37 and attach the outer ends of both cords 34 and 35 to this single weight, but this is not nearly

such a desirable arrangement, as the cord 34 25 would be slackened when pulling up the weight the short distance required to release the cord 35 from the sash.

What I claim is:

In combination with a sash adapted to 30 slide up and down and pulleys suitably supported at the top of the window casing, a pair of sash cords being connected to each side of said sash, a weight compartment arranged at one side only of the casing, a pair 35 of separate weights both arranged to slide in said compartment one above the other, the lowermost one of said weights being connected to one of the sash cords, the uppermost weight being slidably arranged on this 40 cord and connected to the other sash cord for the purpose herein set forth.

Signed at St. Laurent, Quebec, Canada, this 11th day of December, 1914.

FRANCOIS DUFRESNE.
